UNITED STATES PATENT OFFICE.

ISABELLE W. SCHMITZ, OF LOS ANGELES, CALIFORNIA.

DESIGN FOR A DOLL BELL.

Application filed December 12, 1928. Serial No. 29,232. Term of patent 7 years.

To all whom it may concern:

Be it known that I, ISABELLE W. SCHMITZ, a citizen of the United States, residing in Los Angeles, county of Los Angeles and State of California, have invented a new, original, and ornamental Design for Doll Bell, of which the following is a specification, reference being had to the accompanying drawing, forming a part thereof.

The figure is a perspective view of a doll bell, showing my new design.

I claim:

The ornamental design for a doll bell, as shown.

ISABELLE W. SCHMITZ.
